FLUID DUMPING APPARATUS

Clarence R. Dale, Los Angeles, Calif., assignor to
 Dale Service Corporation, Culver City, Calif.,
 a corporation of California

Application June 1, 1937, Serial No. 145,778

17 Claims. (Cl. 166—19)

This invention has to do with improvements in apparatus for dumping fluids within wells, such devices comprising, generally speaking, a body or container for the fluid having a normally closed outlet, and means for opening the outlet to dump the fluid charge by movement of the apparatus when lowered to the proper depth in the well. The present apparatus may be more particularly characterized as being of the type in which the fluid outlet is controlled by a valve and the valve is operated by virtue of relative movement of certain parts upon withdrawal movement of the body.

Among the general objects of the invention is to provide a fluid dumping apparatus capable of accurate control and positive operation to deposit fluid in the place desired, and to avoid accidental release of the fluid charge before that place is reached. It will be understood of course that the present apparatus may be used for handling various fluids, although it is particularly suitable for dumping and distributing liquid mud within the well. Other objects of the invention pertain to various features of construction that are responsible for the improved operative and structural advantages of the apparatus.

All these objects and advantages of the invention can best be explained without necessity for further preliminary discussion, from the following detailed description of the invention in one of its typical and illustrative forms. Throughout the description reference is had to the accompanying drawing in which:

Fig. 1 is a view mainly in elevation, showing the lower portion of the apparatus dropped into engagement with a casing liner;

Fig. 2 is an upper continuation of that portion of the apparatus shown in Fig. 1, certain of the parts being shown in section and the well casing being omitted from the view;

Fig. 3 is a fragmentary view showing the valve and lock parts in released positions; and

Fig. 4 is a fragmentary section taken in the aspect of line 4—4 of Fig. 3, showing a modified form of the invention.

The apparatus may be described generally as comprising an upper hollow body section 10, a lower or mandrel section 11, and valve means 12 normally closing the fluid discharge outlet of the body. The valve 12 is releasably held in closed position by a locking device, generally indicated at 13, which is releasable by relative longitudinal movement between the body and mandrel to permit the valve to open. Referring particularly to Fig. 2, the body 10 comprises an

elongated tubular section 14 connected at its upper end by coupling 15 with a cable 16, or any other suitable suspension means. The fluid containing chamber 17 within the body is vented through opening 18 in the suspension coupling 15. The 5 end of body section 14 is connected by coupling 19 with a lower tubular section 20 having a counterbore 21 receiving telescopically the upper end of mandrel 11, as will later appear. If desired, a plate 22 having a somewhat restricted orifice 23 10 may be retained within the upper end of section 20 by coupling 19, for the purpose of restricting, when the valve is open, the fluid flow from chamber 11.

The lower mandrel section 11 of the apparatus 15 comprises an elongated tube 24 whose upper end is received within counterbore 21 of the body. The body and mandrel have capacity for relative longitudinal movement within the limits of engagement of the mandrel carried pins 25, see Fig. 20 4, with the ends of elongated body slots 26. Suitable means may be provided on the mandrel for frictionally or yieldably engaging the casing or an abutment therein, such as the upper end of a liner 28, to arrest downward movement of the 25 mandrel for the purpose of releasing the locking device 13. As typical, I show such means to comprise an assembly of outwardly bowed resilient members 29 having noduled projections 29a and attached at their upper and lower ends 30 by screws 30 to flanged sleeves 31 and 32. As the apparatus is being lowered within the casing 27, the spring bow and sleeve assembly is supported by bearing ring 33 and a sleeve nut 34 threaded on the lower end of the mandrel. Sleeves 31 and 35 32 are rotatable and slidable longitudinally with relation to the mandrel, to permit the body and mandrel assembly to at all times remain in normal position independently of the spring bows, thereby preventing the cable from winding up, 40 and to permit the mandrel to be lowered relative to the spring bows to valve releasing position.

The valve assembly 12 comprises a tubular member 35 threaded or otherwise retained within the lower body section 20 directly above counterbore 21. The lower portion of member 35 has a bore 36 that may be regarded as the fluid outlet. Normally the outlet is closed by a ball valve 37 supported on the upper end of mandrel 24, the valve having just slightly smaller diameter than the outlet bore 36 and being sufficiently elevated within the outlet to close the latter. During the lock releasing operation, the body moves downward a short distance relative to the mandrel from the position of Fig. 2, as permitted by the 55

normal spacing at 38 between the upper end of the mandrel and shoulder 39, and the upward displaceability of the valve 37 within bore 36. Preferably the body and mandrel will have a 5 telescopic sliding fit within bore 21.

The locking device 13 that releasably holds the valve in closed position, comprises a pair of latch elements in the form of spring fingers 41 attached at their upper ends by screws 42 to the 10 lower surface of the body. In the position of Fig. 2, the lower hooked ends 41a of the spring fingers engage the mandrel within an annular recess 43 formed in the lower end of a collar 44 held in 15 fixed position on the mandrel. When released from collar 44, the resiliency of the spring fingers 41 causes them to spring outwardly to released 20 positions as indicated in Fig. 3. A coil spring 45 encircling the mandrel between the lower end of the body and collar 44 acts to thrust the mandrel downward to keep the spring fingers 41 in locking 25 engagement with the mandrel collar. The purpose of spring 45 primarily is to keep the parts so engaged before the apparatus is loaded with fluid. After chamber 17 is filled, the fluid load transmitted by way of the valve 37 to the mandrel, keeps collar 44 pressed downward into retained engagement with the hooked ends of the spring fingers.

In operation, the body chamber 17 is loaded 30 with fluid and the apparatus is lowered into the well. Assuming the casing to contain a liner for arresting downward movement of the mandrel, the apparatus is lowered until the spring bows 29 come into engagement with the upper 35 end of the liner 28. Upon continued lowering of the apparatus, collar 47 secured to the mandrel comes into engagement with sleeve 31 to arrest further downward movement of the mandrel. Upon continued lowering of the body through 40 the short distance required to withdraw the hooked ends 41a of the spring fingers from within recess 43, the fingers spring outwardly to the positions of Fig. 3, releasing the body for upward movement relative to the mandrel. By now raising the body, the outlet 36 is opened by upward movement from the valve, and as the body continues to move upwardly, yoke 48 comes into engagement with the head 49 of a rod or bolt 50 attached to the valve, to raise the latter from 45 seating position on the upper end of the mandrel. Thereupon, the fluid is discharged from chamber 17 downwardly from the outlet 36 into the mandrel bore 51, and finally out of the lower end of the mandrel into the well.

The present apparatus has the advantage of 55 enabling a body of cement to be deposited on a surface within the well, for example on top of a previously placed quantity of cement, without permitting objectionable dilution of the cement charge with well fluid while the charge is being dumped. By reason of the spring elements 29 being mounted above the lower end of the tubular member 24, its discharge outlet 51 at the lower end may be brought immediately above the surface upon which the cement is to be placed. Then, after the valve is opened, the apparatus 60 may be raised substantially at a rate corresponding to the rate at which the level of the deposited cement rises within the well, so that at no time 65 will the cement during its discharge be required to settle through well fluid in a manner that would cause excessive dilution of the cement.

Some of the fluid may flow outwardly through 70 the upper portions of slots 26 extending above the 75 mandrel in the open position of the valve parts.

If it is desired to confine the entire fluid discharge to the lower end of the mandrel, slots 26 may be closed in any suitable manner, as by means of plates 53 illustrated in Fig. 4. When used for dumping liquid mud into the well, distribution of 5 the mud throughout a considerable length of the well bore may be made by continuing to elevate the apparatus while the mud is being dumped. As previously mentioned, extended distribution of 10 the mud may be facilitated by restricting the discharge from the fluid chamber 17 as by means of the orifice plate 22.

Finally it may be mentioned that the apparatus may be used as a "bottom dump" bailer as well as one operating to discharge the fluid at 15 some intermediate point in the well casing or bore. By lowering the apparatus, either with or without the spring bows 29 mounted thereon, until the lower end of the mandrel 11 bottoms on the hole, the lock 13 may be released by slight 20 continued downward movement of the body, and the fluid charge dumped by then elevating the apparatus, all in the manner previously explained.

I claim:

1. In an apparatus for dumping fluid within wells, a tubular body having a downwardly opening fluid outlet, an elongated tubular member extending below and movable vertically with relation to said body, said member having a discharge 30 opening at its lower end, means carried by said member above said discharge opening for frictionally engaging a liner within the well, a valve normally closing said outlet, and valve control mechanism whereby relative vertical movement 35 between said body and member opens said valve and causes fluid to be discharged from said outlet downwardly through the bore of said tubular member.

2. In an apparatus for dumping fluid within 40 wells, a tubular body having a downwardly opening fluid outlet, an elongated tubular member extending below and movable vertically with relation to said body, said member having a discharge opening at its lower end, means rotatably mounted on said member above said discharge opening for frictionally engaging a liner within the well, a valve normally closing said outlet, and valve control mechanism whereby relative vertical movement 45 between said body and member opens said valve and causes fluid to be discharged from said outlet downwardly through the bore of said tubular member.

3. In an apparatus for dumping fluid within well pipe, a tubular body having a downwardly opening fluid outlet, a depending tubular member extending upwardly within and movable vertically with relation to the lower end of said body, a valve normally supported by said tubular member to close said outlet, valve control mechanism whereby upward movement of said body relative to said member opens the valve and causes fluid to be discharged from said outlet downwardly through the bore of said tubular member, and means carried by said member for 55 frictionally engaging the well pipe.

4. In an apparatus for dumping fluid within well pipe, a tubular body having a downwardly opening fluid outlet, a depending tubular member extending upwardly within and movable vertically with relation to the lower end of said body, a ball valve normally closing said outlet and supported on the upper end of said tubular member, valve control mechanism whereby upward movement of said body relative to said 70 member opens the valve and causes fluid to be discharged from said outlet downwardly through the bore of said tubular member.

ber being downwardly movable with relation to said body to cause the valve to open downwardly, a rod attached to and extending upwardly from said valve, and means carried by the body and engageable by said rod to limit opening movement of the valve whereby fluid discharged from the outlet passes downwardly into said tubular member.

15. In an apparatus for dumping fluid within wells, a tubular body having a downwardly opening fluid outlet, a tubular member extending below said body, a valve normally supported by said member and closing said outlet, said member being downwardly movable with relation to said body to cause the valve to open downwardly, means limiting the opening movement of the valve relative to the body whereby fluid discharged from the outlet passes downwardly into said tubular member, and releasable locking means holding said member in valve closing position.

16. In an apparatus for dumping fluid within wells, a tubular body having a downwardly opening fluid outlet, a tubular member extending below said body, a valve normally supported by said member and closing said outlet, said member being downwardly movable with relation to

said body to cause the valve to open downwardly, means limiting the opening movement of the valve relative to the body whereby fluid discharged from the outlet passes downwardly into said tubular member, releasable locking means holding said member in valve closing position, and yielding means holding the locking means in locked condition.

17. In an apparatus for dumping fluid within wells, a tubular body having a downwardly opening fluid outlet, a tubular member extending below said body, a valve normally supported by said member and closing said outlet, said member being downwardly movable with relation to said body to cause the valve to open downwardly, means limiting the opening movement of the valve relative to the body whereby fluid discharged from the outlet passes downwardly into said tubular member, and releasable locking means holding said member in valve closing position, said locking means comprising a shoulder on the outside of said member, and a resilient locking element carried by the body and engaging said shoulder, said element being releasable from said shoulder by upward movement of said member relative to the body.

CLARENCE R. DALE.
